ELECTRON DISCHARGE TUBE

Max Knoll and Rudolf Rzehulka, Berlin, Germany, assignors to Telefunken Gesellschaft für Drahtlose Telegraphie m. b. H., Berlin, Germany, a corporation of Germany

Application March 6, 1934, Serial No. 714,261
In Germany November 5, 1932

1 Claim. (Cl. 250—27.5)

The present invention relates to an electron discharge tube for the rectification, amplification and production of oscillations, and is provided with a flat cathode surface as the electron source. 5 A flat cathode is understood to be an incandescent cathode of rectangular, square-shaped, or similarly formed section such as an elliptical section, the electron emitting surface of which forms a plane or nearly plane surface. Discharge 0 tubes provided with such cathodes, due to the relatively simple mounting of the cathode and of the electrode system cooperating therewith, offer essential constructive advantages, and furthermore afford obtaining of great steepness due 5 to the relatively large cathode surface.

In such tubes it is advantageous to arrange the auxiliary electrodes, such as control grid and anode, in planes parallel to the cathode surface. 10 Tests have proven that the actual steepness of such arrangements is less than that when calculated from the emitting surface, and that the characteristic at its upward course does not reveal the required sharp bend (Fig. 1) but a smooth course (Fig. 2) so that the expected 15 height of the mutual conductance is not attained. The cause of this behavior is to be seen in the fact that with a definite control voltage of the electrode system there corresponds respective locally different field intensities at the flat and 20 curved or end portions of the cathode surface.

This invention resides in the fact that the electron emission from the narrow sides or edges of the cathode is suppressed, so that the emission is limited to the plane or nearly plane parts of 25 the cathode surface. In this manner the maximum steepness corresponding with the size of the emitting surface, and a very sharp bend in the characteristic curve are obtained. The main object of the invention can best be accomplished 30 by shielding the emission from the cathode edges or borders, by suitably shaping the cathode itself, or by proper shaping and spacing of the electrodes next to the cathode. It is necessary that 35 the field intensity produced by the control electrode or useful electrode be equally great at all points of the cathode surface which contribute to the emission. This can be accomplished by 40 omitting the emitting substance from the edges 0 of the cathode, or by extending the cathode in the direction of the narrow sides by means of auxiliary electrodes, or in so forming the parts 5 of the electrodes (for instance bars of a control grid) opposite the cathode edges that the field intensity at the cathode edges is greatly reduced or 10 becomes negative in comparison with the field intensity at the remaining cathode surfaces.

The accompanying figures show embodiments of the invention by way of example.

Figures 3 and 4 show front and plan views, respectively, of an embodiment of a triode in which the support rods 4 and 5 of the control grid serve 5 as screens and simultaneously to reduce the field intensity at the cathode edges. The flat cathode 1 which is of the indirectly heated type, is fixedly secured in openings of insulating bridges 13 and 14 by means of extensions 8, 9 and 10, 11 at the 10 upper and lower ends of the cathode, respectively. The grid support rods or bars 4 and 5 and the anode supports 15 and 16 are also threaded through suitable openings in the insulating bridges. The grid bars 4 and 5 are wide enough 15 to cover the narrow sides 2, 3 of the cathode; the diameter of the rods and their distance from the narrow sides of the cathode is suitably approximately equal to the inner diameter of the grid.

Figure 5 shows a section through a pentode 20 whose flat cathode 11 is not covered at the edges 21 and 31 by emitting substance. Only the wide surfaces of the cathode are provided with layers 12 of emitting substance. Successively surrounding the cathode are control grid 61, screen grid 62, 25 suppressor grid 63 and anode 71.

Figure 6 shows the section of a triode having 30 a flat cathode 21 whose electrical field in the direction of its two narrow sides or edges 22 and 23 is extended by means of two auxiliary electrodes 24 and 25. The cathode 21 and the auxiliary electrodes 24 and 25 are maintained at a suitable equal potential and are surrounded by 35 control grid 26 and anode 27.

Figure 7 represents a plan view of a triode 40 having a square-shaped cathode 31. Adjacent to the four corners 32, 33, 34 and 35 of cathode 31 are the shields 37, 38, 39 and 40 which are connected to and serve to support the control electrode 36 45 placed between the anode 41 and the cathode.

What we claim is:

An electron discharge tube comprising an elongated indirectly heated, flat-shaped cathode, substantially rectangular in cross section, a plurality of cooperating electrodes completely surrounding the cathode and having their support rods in alignment with the narrower side edges of the cathode, the support rods of the electrode immediately adjacent the cathode being spaced 50 from said cathode edges a distance equal to substantially the diameter of said rods, which diameter is substantially wider than the cathode side edges, whereby to effectively shield the cooperating electrodes from electrons emitted from the 55 cathode edges.

MAX KNOLL.
RUDOLF RZEHULKA.
